UNITED STATES PATENT OFFICE.

FRED R. BUMPUS AND JOHN KYLE, OF FRANKLIN, PENNSYLVANIA.

FLOOR-DRESSING MACHINE.

No. 817,041.

Specification of Letters Patent.

Patented April 3, 1906.

Application filed August 31, 1905. Serial No. 276,552.

To all whom it may concern:

Be it known that we, FRED R. BUMPUS and JOHN KYLE, citizens of the United States, residing at Franklin, in the county of Venango 5 and State of Pennsylvania, have invented new and useful Improvements in Floor-Dressing Machines, of which the following is a specification.

This invention relates to machines for levelling and smoothing floors; and our improvements consist in a frame having rear supporting-wheels, a truck mounted on wheels, means for adjustably connecting the forward part of the frame with the truck, a floor-dressing roller journaled in the front end of the frame, and means for simultaneously operating the floor-dressing roller and machine, as hereinafter described.

Our improvements further consist in certain combinations and arrangement of parts, all of which are hereinafter fully described and specifically claimed.

Referring to the drawings, Figure 1 represents a side elevation of the machine as when ready for operation. Fig. 2 is a view of the front end thereof. Fig. 3 shows a modification of the means employed for operating the dressing or smoothing device. Fig. 4 is an enlarged sectional view of the floor-dressing 30 roller with means for holding sandpaper or emery-cloth thereon. Figs. 5 and 6 represent metallic plates having roughened or cutting surfaces for action on the projecting surfaces of the floor. Fig. 7 is a perspective 35 view of an auxiliary end roller.

On the drawings the numeral 1 designates the frame of the machine, which somewhat resembles that of a bicycle or velocipede. The sides 2 3 of this frame are similar in outline, 40 resembling somewhat the letter A, with the lower ends thereof connected by duplicate horizontal side bars 4, the rear ends of which are connected by journal-boxes 5 with an axle 6, having supporting-wheel 7 at each end thereof. The forward ends of the side frames are each provided with suitable journal-bearings for receiving the ends of a shaft 8, on which is secured the floor-dressing roller 9, the periphery of which is provided with a longitudinal groove 10 to receive a locking-wedge 11, which is preferably formed of 50 spring-steel, so as to securely hold the opposite ends of the emery-cloth or sandpaper with which the roller is wrapped when the smoothing or finishing touches are given the floor. However, before the application of

sandpaper or emery-cloth to the aforesaid roller a series of steel plates 12, file-cut or rasped, are bolted or otherwise secured around the periphery of the roller, so as to 60 cut down all projections and reduce the floor-surface to a perfect level, which being accomplished the said steel plates 12 are removed from the roller and the sandpaper or emery-cloth substituted therefor, as above mentioned.

In the rear of the roller 9 the side frames are connected with a transverse frame or truck 13, having supporting end wheels 14, the truck being provided with adjusting-screws 15, whereby the roller is relieved of superfluous weight and a proper level thereof maintained. A scoop or dust-catcher 16 is connected with the truck 13 on the forward part of the frame to receive the dirt or dust 75 resulting from the action of the roller 9 during the working of the machine. The upper part of the side frames are each provided with a journal-bearing for receiving the journals of a driving-shaft 17, having end cranks 80 18 provided with handles 19, within comfortable reach of which the rear of the machine is provided with an operator's seat, as shown at 20 in Fig. 1. The horizontal bar 21 of the A-shaped side frames are each provided with 85 journal-bearings to receive the end journals of a transverse shaft 22, carrying a sprocket-wheel 23 and pinion 24, the former adapted to be driven by a chain 25 from a pinion 26 on the driving-shaft 17, the pinion 24 serving 90 to transmit motion through a chain 26' to a sprocket-wheel 27, secured on the rear axle 6 of the machine.

The working roller 9 receives motion from the driving-shaft 17 through a bevel-wheel 95 28, mounted on said shaft, a pinion 29 engaged therewith and keyed or otherwise secured to the upper part of a rod 30, which is journaled in suitable bearings forming part of or connected with the forwardly-inclined 100 member 31 of one of the A-shaped side frames of the machine, the lower part of the rod 30 being provided with a second pinion 32 to engage a bevel-wheel 33 on the adjacent end of the working roller.

In lieu of the roller-driving mechanism described the driving-shaft may be provided with a cog-wheel 34, as shown in Fig. 3, the said cog-wheel being adapted to engage through an idler 35 a pinion 36, the shaft 37 of which is provided with a sprocket-wheel 38, from which power is transmitted through 110

a chain 39 to sprocket-pinion 39', connected with the shaft of the working roller 9.

The forward part of the machine is provided with a guard-plate or bar 40, which is intended to contact with the base-board of the room before the working parts of the machine can injure the walls thereof.

The traction - wheels of the machine are provided with rubber tires to insure frictional contact with the floor, as well as to prevent scratching or marring the same.

To provide for finishing up to the base-board, auxiliary end rollers *b* are adapted to be temporarily secured on the projecting ends of the roller-shaft 8, as shown in dotted lines at *b* in Fig. 2, rubber or other suitable fenders *a* being secured to the ends of the aforesaid shaft to prevent same from marring the wall or base-board thereof.

Having described the invention, what is claimed, and desired to be secured by Letters Patent, is—

1. In a floor-dressing machine, the combination with a frame having supporting-wheels at the rear end thereof, and a supporting-truck connected with the forward part of same, a floor-dressing roller journaled in the

front end of the frame, means connected with the truck for changing the elevation of the forward part of the frame and means for simultaneously operating the dressing - roller and propelling the machine.

2. The combination in a floor-dressing machine, of a frame having supporting-wheels at the rear thereof, a truck and means whereby the forward part of the frame is adjustably connected therewith, a shaft journaled in the frame in advance of the truck having mounted thereon dressing - rollers, one of which being located between the sides of the frame and the others upon each end outside of the frame, a driving - shaft and separate means for transmitting motion from said shaft to propel the machine and operate the floor-dressing rollers thereof, as set forth.

In testimony whereof we have hereunto set our hands this 26th day of August, A. D. 1905.

FRED R. BUMPUS.
JOHN KYLE.
